UNITED STATES PATENT OFFICE.

JOHN STEPHENSON, OF NEW YORK, N. Y.

DESIGN FOR A CAR-TRUCK FRAME.

SPECIFICATION forming part of Design No. 19,299, dated September 3, 1889.

Application filed August 2, 1889. Serial No. 319,580. Term of patent 14 years.

To all whom it may concern:

Be it known that I, JOHN STEPHENSON, a citizen of the United States, residing in the city, county, and State of New York, have invented a certain new and original Design for Car-Truck Frames, of which the following is a specification.

The figure of the drawing is a perspective view of a car-truck illustrating my design for the frame thereof.

The leading feature of the design is the peculiar shape of the frame, consisting of the parts connected and arranged as will now be described.

There are two parallel sills A A, two shorter inner sills B B, parallel to each other and to the outer sills, and two composite cross-bars C C, each consisting of two parts a b, crossing each other diagonally and connecting the

sills A A and B B, as shown. As thus designed, there is presented to the eye a hexagonal frame B B C C within the outer parallel supporting-sills A A.

What I claim is—

The design for a car-truck frame herein shown and described, the same comprising the outer sills A A, inner parallel sills B B, and bars C C, each consisting of the bars a b, crossing each other diagonally, substantially as described.

In testimony whereof I have signed my name to this specification in the presence of two subscribing witnesses.

JOHN STEPHENSON.

Witnesses:

STUART A. STEPHENSON,
JOS. B. STEPHENSON.
